(57) **CLAIM**

The ornamental design for a measuring device assembly as shown and described.

DESCRIPTION

FIG. 1 is an exploded top right front perspective view of the measuring device assembly.

FIG. 2 is a top front right perspective view of the measuring device assembly.

FIG. 3 is a bottom front right perspective view of the measuring device assembly.

FIG. 4 is a top back left perspective view of the measuring device assembly.

FIG. 5 is a bottom back left perspective view of the measuring device assembly.

FIG. 6 is a top view of the measuring device assembly.

FIG. 7 is a bottom view of the measuring device assembly.

FIG. 8 is a right side view of the measuring device assembly.

FIG. 9 is a left side view of the measuring device assembly.

FIG. 10 is a front view of the measuring device assembly; and,

FIG. 11 is a back view of the measuring device assembly. The broken lines shown are included for the purpose of illustrating portions of the measuring device assembly and form no part of the claimed design.

1 Claim, 6 Drawing Sheets
